LEVERAGE SYSTEM

Ernest C. Neal, Chicago, Ill., assignor of one-half
to Elmer Brandell, Chicago, Ill.

Application August 9, 1945, Serial No. 609,769

18 Claims. (Cl. 164—41)

1

This invention relates in general to power multiplying leverage systems and has more particular reference to a compound lever mechanism providing for the movement of an actuated lever member about its fulcrum, by the application of force to a fulcrum remote portion of the lever member, through the medium of a driving lever having moving contact with a surface of the lever member at said remote portions, the present application, relating especially to the combination of the leverage system with ratchet mechanism in power tools, and comprising a continuation in part of copending application for United States Letters Patent, Serial No. 520,400, filed January 31, 1944, now Patent 2,385,835, issued October 2, 1945, for lever construction.

An important object of the invention is to provide compact and efficient means for imparting relative movement in an actuated lever, through the application of force applied to a fulcrum remote portion of the lever; a further object being to apply lever moving force through the action of a driving lever whereby to accomplish maximum power multiplication at a minimum expenditure of effort; a still further object being to so arrange and mount the driving lever that maximum power multiplication may be accomplished during a selected or desired portion of its operating stroke.

Another object is to apply force to the actuated lever by means of a roller or other power applying element on the driving lever and to so mount the levers that the roller may alter its point of engagement on one of the levers, with respect to the fulcrum of said lever, in order to determine maximum power multiplication during a desired portion of the operating stroke of the mechanism.

Another important object is to so arrange the driving and driven levers that the power transfer roller, during the performance of a power stroke, may roll, substantially without frictional loss, first in one direction and then in the reverse direction on one of the levers with respect to the fulcrum of such lever.

Another important object is to utilize the movement imparted in the driven lever for the operation of a pawl and ratchet mechanism; a further object being to incorporate the lever driven pawl and ratchet in power tools of various sorts including rod and cable cutters, jack mechanisms and other tools and devices incorporating pawl and ratchet mechanisms for power transmitting purposes.

The foregoing and numerous other important

5 objects, advantages, and inherent functions of the invention will become apparent as the invention is more fully understood from the following description, which, taken in conjunction with the following drawings, discloses a preferred embodiment of the invention.

Fig. 1 is a fragmentary side view showing a pawl and ratchet power transmitting mechanism embodying power multiplying levers incorporating the present invention;

Fig. 2 is a view showing a modified form of the power multiplying levers;

Fig. 3 is a view showing the levers of Fig. 2 used for pawl driving purposes;

Fig. 4 is an elevation view of a rod and cable cutter embodying pawl and ratchet power transmitting means actuated by power multiplying levers in accordance with the present invention;

Fig. 5 is a view in vertical section through a 10 lifting jack embodying the present invention;

Fig. 6 is a view taken substantially along the line 6—6 in Fig. 5; and

Fig. 7 is a sectional view taken substantially 15 along the line 7—7 in Fig. 5.

To illustrate the invention the drawings show, in each case, a support frame 11 carrying a pair of cooperating levers 12 and 13 pivoted on the frame 11, the lever 12 having a fulcrum pivot 14 and the lever 13 a fulcrum pivot 15 supported in the main frame 11. The lever 12 comprises a driving lever preferably adapted for manual operation about its fulcrum pivot 14, the lever 13 being driven about its fulcrum pivot 15 in response to the driving movement of the lever 12.

To this end the lever 13 has a fulcrum remote bearing portion or surface 16 in position to receive thrust imparted by the lever 12. The lever 12 is provided with a thrust member 17 in position to bear upon the surface 16. The thrust member 17 preferably comprises a roller mounted on a pin 18, on the lever 12, preferably located near the fulcrum pivot 14, whereby substantial power multiplication may be accomplished as a result of power application at the fulcrum remote end of the lever 12 and transferred to the lever 13 through the transfer element or roller 17.

The bearing surface 16 of the lever 13 is remote from the fulcrum pivot 15; and the levers 12 and 13 are so mounted that the bearing portion 16 normally extends on the side of the fulcrum pivot 14 remote from the fulcrum pivot 15. The fulcrum pivot 14 of the lever 12 thus lies more or less intermediate the bearing portion 16 and the fulcrum pivot 15. The parts are also preferably arranged so that the area of

contact between the surface 16 and the member 17, at the commencement of an operating stroke, lies on one side of the plane which passes through the axes of the lever pivots 14 and 15, such area of contact moving during the performance of a power stroke, through such plane of pivots, to the opposite side thereof.

It will be seen that the member 17, during the performance of a power stroke, will initially travel on the surface 16 in a direction away from the fulcrum pivot 15, thus initially increasing the distance from said pivot 15 of the application of thrust, by the lever 12, on the lever 13, thereby improving the power multiplying effect of the mechanism during the initial and intermediate portions of an operating stroke. At the conclusion of the operating stroke, the member 17 may retrogress on the surface 16, thereby diminishing the power multiplying effect during the terminal portions of an operating stroke; or the mechanism may be arranged, by suitably predetermining the location of the pivots 14 and 15, and the shape of the lever 13 including the shape and inclination of the surface 16, in order to accomplish maximum power multiplication at the end of the stroke. Usually, however, it is desirable to accomplish maximum power multiplication during the medial portions of the operating stroke where maximum power multiplying effect is ordinarily desired.

The driven movement of the lever 13 may, of course, be employed to accomplish any desired work. As shown in Figs. 1, 3, 4 and 5, the movement of the lever may be utilized to drive a pawl for the operation of a suitably toothed pawl driven member. This driven member, as shown in Fig. 1, may take the form of a ratchet wheel 20 driven by a pawl 19. In the Fig. 3 embodiment, a pawl 319 serves to drive a ratchet wheel 320. The arrangement shown in Fig. 4 comprises a ratchet wheel 420 actuated by a pawl 419, while, as shown in Fig. 5, the toothed element may comprise a rack 520, driven by a pawl 519.

As shown in Figs. 3, 4 and 5, the driving pawl may be connected directly on the lever 13, as by means of a suitable pivot pin 21, mounted on the lever, or, as shown in Fig. 1 of the drawings, the pawl 19 may be pivoted, as at 21', on an intermediate pawl carrying lever 22 having a thrust receiving member, such as a roller 23, at an end thereof in position to engage a preferably arcuate driving surface 24 on the lever 13. Alternatively, the lever 13 may be drivingly connected with the lever 22 by means of a connecting link or other driving element.

The various elements of the mechanism may be biased, as by gravity, by springs, or by the resistance of work to be accomplished, toward an initial or starting position. As shown in Fig. 1 of the drawings, the lever 22, which is pivoted in the frame 11, is provided with spring means 25, operatively connected between the lever 22 and the frame 11, which yieldingly urges the lever 22 toward a retracted, initial or starting position. When in such position, the pressure of the roller 23 upon the lever 13 urges it and also the operating lever 12 toward the initial or starting position. As the lever 12 is drawn or moved in a counter-clockwise direction from the initial position shown in Fig. 1, the roller 17 will press upon the bearing surface 16 and turn the lever 13 on its fulcrum pivot in a counter-clockwise direction, viewing Fig. 1. Such movement of the lever 13 will move the lever 22 in a clockwise direction about its pivot, against the influ-

ence of the spring 25, and will move the pawl 19 to drive the ratchet wheel in the direction of the arrow.

During the operating stroke of the mechanism, the roller 17 may travel outwardly of the pivot 15 on the surface 16 thereby increasing the power multiplying effect of the leverage mechanism until the roller reaches its maximum displacement outwardly of the fulcrum pivot 15, which will occur approximately when the axes of the pivots 14, 15 and 18 lie in a common plane, the distance between the roller and the fulcrum pivot 15 decreasing after the axis of the roller passes through such common plane. The pawl and ratchet mechanism and the lever 22, also the arrangement of the driving connection between the levers 13 and 22, may be arranged so that the mechanism accomplishes maximum power multiplication when the pawl has shifted the ratchet 20, 320, 420 or 520, as the case may be, through a desired displacement, such as a ratchet wheel displacement necessary to advance the wheel through the pitch distance between its teeth in order to allow operation of a holding pawl, shown at 26, 26¹ and 26², in Figs. 3, 4 and 5 respectively.

As shown in Fig. 3 of the drawings, the pawl 319 is pivotally connected directly on the lever 13 and extends thence in position to drivingly cooperate with the ratchet wheel 320, rotatably mounted in the frame 11. The frame 11 may also carry the holding pawl 26 suitably biased toward operative engagement with the ratchet wheel. A spring 27 may be connected between a pin 28 on the lever 13 and a mounting pin 29 on the frame 11 to normally urge the lever 13 and its cooperating driving lever 12 toward the retracted position shown in Fig. 3.

By moving the driving lever 12 in a counter-clockwise direction on its fulcrum pivot 14, the transfer element or roller 17 may be caused to press upon the bearing surface 16 and roll thereon initially outwardly of the pivot 15 to turn the lever 13 in a counter-clockwise direction on said pivot 15. Such movement of the lever 13 may terminate when it reaches the dotted line position, shown in Fig. 3, in which position the pawl 319 will have turned ratchet wheel 320 through a displacement sufficient to allow the holding pawl 26 to drop into and lock with the next succeeding tooth of the ratchet wheel. Suitable spring means 35 may be associated with each of the pawls 319 and 26 in order to yieldingly urge the same into operative engagement with the ratchet wheel 320.

The power multiplying leverage and ratchet arrangement of the present invention, as shown in Fig. 4 of the drawings, may be applied to advantage in a rod or cable cutter in which the frame 11 forms a cutting jaw 30, while the ratchet wheel 420 forms a cooperating cutting jaw 31, the parts being connected together for pivotal movement about a pivot pin 32 and normally urged toward jaw open position, as by means of a spring 33 bearing at its opposite ends respectively on members 11 and 420. To stop the members 11 and 420 in jaw open position, cooperating stops, comprising a pin 30' on one member and a cooperating projection 31' on the other, may be provided. The frame 11 in this embodiment may be provided with an upstanding handle 34 so that by grasping the handle 34 the device may be steadied in operative position. The driving lever 12 also forms a handle extending generally adjacent the handle 34. By drawing the fulcrum

remote end of the handle 12 away from the handle 34, the lever 12 will be turned on its pivot 14 in a clockwise direction, viewing Fig. 4, thus causing the roller 17 to press upon and ride along the surface 16 initially in a direction away from the pivot 15, thereby turning the lever 13 in a clockwise direction on its pivot 15 with progressively increasing force until the roller passes through the plane of the pivots 14 and 15. Resulting movement of the lever 13 in a clockwise direction, viewing Fig. 4, will cause the pawl 419, pivoted thereon, to engage the teeth of the ratchet member 420 and turn it in a counter-clockwise direction on the pivot 32, thereby forcing the cutting jaw 31 toward the cooperating jaw 30. The parts may be so arranged that the pawl 419, during an operating stroke of the lever 12, will advance the member 420, against the influence of the spring 33, through a displacement equal to the pitch distance between adjacent teeth of the member 420. A pawl 26', pivoted on the frame 11, may be provided to prevent retrogressive movement of the member 420 under the influence of the spring 33.

Spring means 35' may be provided on the frame 11 to normally urge the pawls 419 and 26' in a direction to engage the teeth of the ratchet member 420. A control lever 36 may also be provided to cooperate with the pawls 419 and 26' for the purpose of releasing the same against the influence of the spring means 35' to allow the cutting member 420 to return to an initial or starting position, under the influence of the spring 33 after the jaws 30 and 31 have been completely closed in the performance of a cutting operation as a result of repeated strokes of the handle 12.

As shown in Fig. 5, the frame 11 forms a jack housing providing a channel in which the rack member 520 is longitudinally movable in cooperation with a holding pawl 26² and the pawl 519 pivoted, as at 21, on the lever 13. Spring means 35² may be employed to resiliently urge the driving and holding pawls 519 and 26² toward operative engagement with the teeth of the rack member 520.

In this embodiment the holding pawl 26² is of split configuration being pivoted in the frame 11, as at 37, on opposite sides of the rack member. By operating the handle 12, the pawl 519 may be moved upwardly in the frame 11 in engagement with the rack 520, the holding pawl 26² snapping over the teeth of the rack member. The rack member 520 may thus be elevated in the frame 11 by repeated reciprocations of the handle 12 within a substantial ninety degree arc from the initial or starting position shown in Fig. 5.

The pawls 519 and 26² may be provided with projecting pins 38 and 39, accessible through an opening 40 in the side of the frame. By manually pressing the pins 38 and 39 the pawls may be released from the rack to allow the same to drop in the frame by gravity, or otherwise, to be forced to a depressed or starting position in the frame. In this connection the lifting pawl 519 may be withdrawn from the rack and guided into a notch 41 in the holding pawl. Thereupon the holding pawl may be withdrawn from the rack by lifting action of the lifting pawl in the notch. Alternatively, a step-by-step rack lowering operation, under pawl control, may be accomplished by rocking the handle 12 and selectively withdrawing the pawls from the rack by manual operation of the pins 38 and 39. If desired, adjustable pawl guid-

ing means may be provided for retracting the pawls selectively and automatically in the performance of a step-by-step rack lowering operation.

As shown in Figs. 4-7 the lever 12 may have a split or forked end comprising the lugs 43 between which the roller 17 is mounted. The frame 11, also, may be provided with spaced walls 44 forming mounting lugs 45 for receiving the pivot pin 14, which is also mounted in the lugs 43. As more particularly illustrated in Figs. 6 and 7, the walls 44, also, may be provided with aligned embossments 46, inwardly of the lugs 45, and threaded to receive mounting plugs 47. The embossments 46 are cut away, as at 48, in the side thereof facing toward the lugs 45. The pivot pin 15 may comprise a member force-fitted in a suitable opening formed in the lever 13, said member having opposite ends projecting on opposite sides of the lever to a length permitting insertion of the lever 13 with attached pivot pin 15, between the lugs 45 and through the opening 48, to centered position with respect to the threaded bosses 46. After the lever 13 has thus been mounted, the mounting plugs 47 may be threadedly engaged in the bosses 46 to form bearings for the opposed ends of the pivot pin 15. The mounting plugs may be secured in position, as by the cotter-pins 49. After assembly of the lever 13, the lever 12 may be pivotally mounted on the lugs 45 by driving the pivot pin 14 through said lugs 45 and the ears 43.

The lever 13, as shown in Figs. 6 and 7, may be formed with a split end forming ears 50 between which the pawl 19 may be pivotally mounted, as on the pin 21; and in order to obtain maximum leverage, the pin 21 is preferably disposed as closely as possible to the pivot pin 15, which may be cut away, as at 51 and 52, in its side facing the pin 21 to allow the pin and the pivoted end of the pawl 19 to be mounted on the lever 13.

In the embodiment shown in Figs. 4 and 5 it is preferable, as a matter of convenience, to link the lever 13 to the lever 12 in order to insure retraction of the lever 13 to the initial or starting position. To this end, the lever 13 may be cut out on one side, as at 53, to receive the end of a tie link 54. The link has an elongated slot 55, at one end, loosely receiving a pin 56 in the lever 13, the other end of the link being pivoted on the lever 12 as on the roller pivot 18. This link will draw the lever 13 to an initial or starting position with the surface 16 in engagement with the roller 17, as shown in Figs. 4 and 5, but will idle the pin 56 in the slot 55 during a power stroke.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the forms herein disclosed being preferred embodiments for the purpose of illustrating the invention.

The invention is hereby claimed as follows:

1. A device of the character described comprising a frame, a ratchet member movably mounted on the frame, a lever member connected for relative turning movement about a lever pivot on the said frame, a driving pawl operatively associated with said ratchet member and drivingly connected with said lever member, a power lever having an end connected for relative turning movement about a fulcrum pivot on said frame

and spaced from said lever pivot, said power lever having a bearing member thereon adjacent said fulcrum pivot and said lever member having an elongated bearing surface extending adjacent said fulcrum pivot in position to engage said bearing member, said bearing member being adapted, during a power stroke of said power lever, to bear upon said surface to turn said lever member on said lever pivot and to ride said surface in a direction initially outwardly of said lever pivot for power multiplying purposes.

2. A device of the character described comprising a frame, a ratchet member movably mounted on the frame, a lever member connected for relative turning movement about a lever pivot on the said frame, a driving pawl operatively associated with said ratchet member and drivingly connected with said lever member, a power lever having an end connected for relative turning movement about a fulcrum pivot on said frame and spaced from said lever pivot, said power lever having a bearing member thereon adjacent said fulcrum pivot and said lever member having an elongated bearing surface extending adjacent said fulcrum pivot, at the side thereof remote from said lever pivot, in position to engage said bearing member and to be moved thereby, during a power stroke of said power lever, from a position engaging said bearing member on one side of the plane including the axes of said fulcrum and lever pivots, to a position engaging said bearing member on the other side of said plane whereby to drive said ratchet member through said pawl.

3. A device of the character described comprising a frame, a ratchet member movably mounted on the frame, a lever member connected for relative turning movement about a lever pivot on the said frame, a pawl operatively associated with said ratchet member and drivingly connected with said lever member, a power lever having an end connected for relative turning movement about a fulcrum pivot on said frame and spaced from said lever pivot, said power lever having a bearing member thereon, said lever member having an elongated bearing surface extending adjacent said fulcrum pivot, on the side thereof remote from said lever pivot, in position to engage and receive thrust from said bearing member, said bearing surface being movable during a power stroke of said power lever, from a position engaging said bearing member on one side of the plane including the axes of said fulcrum and lever pivots, to a position engaging said bearing member on the other side of said plane whereby to apply maximum driving effect to said ratchet member, through said pawl, during medial portions of the operating stroke of said power lever.

4. A device of the character described comprising a frame, a ratchet member movably mounted on the frame, a lever member connected for relative turning movement about a lever pivot on the said frame, a driving pawl operatively associated with said ratchet member and drivingly connected with said lever member, a power lever having an end connected for relative turning movement about a fulcrum pivot on said frame and spaced from said lever pivot, said power lever having a bearing member thereon adjacent said fulcrum pivot, and said lever member having an elongated bearing surface extending adjacent said fulcrum pivot in position to engage said bearing member, said bearing member being adapted, during a power stroke of said lever, to bear upon said surface to turn said lever member

on said lever pivot and to ride said surface in a direction initially outwardly of said lever pivot for power multiplying purposes whereby to drive said ratchet member through said driving pawl, and a holding pawl for holding the ratchet member against retrogressive movement.

5. A device of the character described comprising a frame, a rack bar movably mounted on the frame, a lever member connected for relative turning movement about a lever pivot on said frame, a driving pawl operatively associated with said rack bar and drivingly connected with said lever member, a power lever having an end connected for relative turning movement about a fulcrum pivot on said frame and spaced from said lever pivot, said power lever having a bearing member thereon adjacent said fulcrum pivot and said lever member having an elongated bearing surface extending adjacent said fulcrum pivot in position to engage said bearing member, said bearing member being adapted, during a power stroke of said lever, to bear upon said surface to turn said lever member on said lever pivot and to ride said surface in a direction outwardly of said lever pivot for power multiplying purposes whereby to drive said rack bar through said driving pawl, and a holding pawl for holding the rack bar against retrogressive movement.

6. A device of the character described comprising a frame, a ratchet member movably mounted on the frame, a lever member connected for relative turning movement about a lever pivot on said frame, a driving pawl operatively associated with said ratchet member and drivingly connected with said lever member, a power lever having an end connected for relative turning movement about a fulcrum pivot on said frame and spaced from said lever pivot, said power lever having a bearing member thereon adjacent said fulcrum pivot and said lever member having an elongated bearing surface extending adjacent said fulcrum pivot in position to engage said bearing member, said bearing member being adapted, during a power stroke of said lever, to bear upon said surface to turn said lever member on said lever pivot and to ride said surface in a direction outwardly of said lever pivot for power multiplying purposes whereby to drive said ratchet member through said driving pawl, a holding pawl for holding the ratchet member against retrogressive movement, and detent means for guiding said pawls out of operative engagement with said ratchet member.

55 7. A device of the character described comprising a frame forming a cutting jaw, a ratchet member movably mounted on the frame forming a cooperating cutting jaw, a lever member connected for relative turning movement about a lever pivot on said frame, a driving pawl operatively associated with said ratchet member and drivingly connected with said lever member, a power lever having an end connected for relative turning movement about a fulcrum pivot on said frame and spaced from said lever pivot, said power lever having a bearing member thereon adjacent said fulcrum pivot and said lever member having an elongated bearing surface extending adjacent said fulcrum pivot in position to engage said bearing member, said bearing member being adapted, during a power stroke of said lever, to bear upon said surface to turn said lever member on said lever pivot and to ride said surface in a direction outwardly of said lever pivot for power multiplying purposes whereby to move

said ratchet member on said frame in a direction to relatively close said jaws.

8. A device of the character described comprising a frame forming a cutting jaw, a ratchet member movably mounted on the frame forming a cooperating cutting jaw, a lever member connected for relative turning movement about a lever pivot on said frame, a driving pawl operatively associated with said ratchet member and drivingly connected with said lever member, a power lever having an end connected for relative turning movement about a fulcrum pivot on said frame and spaced from said lever pivot, said power lever having a bearing member thereon adjacent said fulcrum pivot and said lever member having an elongated bearing surface extending adjacent said fulcrum pivot in position to engage said bearing member, said bearing member being adapted, during a power stroke of said lever, to bear upon said surface to turn said lever member on said lever pivot and to ride said surface in a direction outwardly of said lever pivot for power multiplying purposes whereby to move said ratchet member on said frame in a direction to relatively close said jaws, and spring means operatively connected between said frame and ratchet members to yieldingly urge said ratchet member and frame relatively toward jaw open position.

9. A device of the character described comprising a frame, a ratchet member movably mounted on the frame, a lever member connected for relative turning movement about a lever pivot on said frame, a driving pawl operatively associated with said ratchet member, a power lever having an end connected for relative turning movement about a fulcrum pivot on said frame and spaced from said lever pivot, said power lever having a bearing member thereon adjacent said fulcrum pivot and said lever member having an elongated bearing surface extending adjacent said fulcrum pivot in position to engage said bearing member, said bearing member being adapted, during a power stroke of said lever, to bear upon said surface to turn said lever member on said lever pivot and to ride said surface in a direction outwardly of said lever pivot for power multiplying purposes, said driving pawl being mounted on an auxiliary lever pivoted on said frame and drivingly connected with said lever member.

10. A device of the character described comprising a frame, a ratchet member movably mounted on the frame, a lever member connected for relative turning movement about a lever pivot on said frame, a driving pawl operatively associated with said ratchet member, a power lever having an end connected for relative turning movement about a fulcrum pivot on said frame and spaced from said lever pivot, said power lever having a bearing member thereon adjacent said fulcrum pivot and said lever member having an elongated bearing surface extending adjacent said fulcrum pivot in position to engage said bearing member, said bearing member being adapted, during a power stroke of said lever, to bear upon said surface to turn said lever member on said lever pivot and to ride said surface in a direction outwardly of said lever pivot for power multiplying purposes, said driving pawl being mounted on an auxiliary lever pivoted on said frame, said lever member having a bearing cam surface in position to drivingly engage said auxiliary lever.

11. A device of the character described comprising a frame, a ratchet member movably

mounted on the frame, a lever member connected for relative turning movement about a lever pivot on said frame, a driving pawl operatively associated with said ratchet member, a power lever having an end connected for relative turning movement about a fulcrum pivot on said frame and spaced from said lever pivot, said power lever having a bearing member thereon adjacent said fulcrum pivot and said lever member having an elongated bearing surface extending adjacent said fulcrum pivot in position to engage said bearing member, said bearing member being adapted, during a power stroke of said lever, to bear upon said surface to turn said lever member on said lever pivot and to ride said surface in a direction outwardly of said lever pivot for power multiplying purposes, said driving pawl being mounted on an auxiliary lever pivoted on said frame and drivingly connected with said lever member, and spring means yieldingly urging said auxiliary lever toward retracted position.

12. A device of the character described comprising a frame, a rack bar forming a lifting jack movably mounted on the frame, a lever member connected for relative turning movement about a lever pivot on said frame, a driving pawl operatively associated with said rack bar and drivingly connected with said lever member, a power lever having an end connected for relative turning movement about a fulcrum pivot on said frame and spaced from said lever pivot, said power lever having a bearing member thereon adjacent said fulcrum pivot and said lever member having an elongated bearing surface extending adjacent said fulcrum pivot in position to engage said bearing member, said bearing member being adapted, during a power stroke of said lever, to bear upon said surface to turn said lever member on said lever pivot and to ride said surface in a direction outwardly of said lever pivot for power multiplying purposes whereby to raise said rack bar in said frame.

13. A device of the character described comprising a frame, a rack bar forming a lifting jack movably mounted on the frame, a lever member connected for relative turning movement about a lever pivot on said frame, a driving pawl operatively associated with said rack bar and drivingly connected with said lever member, a power lever having an end connected for relative turning movement about a fulcrum pivot on said frame and spaced from said lever pivot, said power lever having a bearing member thereon adjacent said fulcrum pivot and said lever member having an elongated bearing surface extending adjacent said fulcrum pivot in position to engage said bearing member, said bearing member being adapted, during a power stroke of said lever, to bear upon said surface to turn said lever member on said lever pivot and to ride said surface in a direction outwardly of said lever pivot for power multiplying purposes whereby to raise said rack bar in said frame, and a holding pawl pivoted on the frame in position to engage said rack bar and prevent retrogressive movement of the same.

14. A device of the character described comprising a frame, a rack bar forming a lifting jack movably mounted on the frame, a lever member connected for relative turning movement about a lever pivot on said frame, a driving pawl operatively associated with said rack bar and drivingly connected with said lever member, a power lever having an end connected for relative turning movement about a fulcrum pivot on said frame and spaced from said lever pivot, said power lever

having a bearing member thereon adjacent said fulcrum pivot and said lever member having an elongated bearing surface extending adjacent said fulcrum pivot in position to engage said bearing member, said bearing member being adapted, during a power stroke of said lever, to bear upon said surface to turn said lever member on said lever pivot and to ride said surface in a direction outwardly of said lever pivot for power multiplying purposes whereby to raise said rack bar in said frame, a holding pawl pivoted on the frame in position to engage said rack bar and prevent retrogressive movement of the same, and spring means normally urging said pawls into operative engagement with said rack bar.

15. A device of the character described comprising a frame, a rack bar forming a lifting jack movably mounted on the frame, a lever member connected for relative turning movement about a lever pivot on said frame, a driving pawl operatively associated with said rack bar and drivingly connected with said lever member, a power lever having an end connected for relative turning movement about a fulcrum pivot on said frame and spaced from said lever pivot, said power lever having a bearing member thereon adjacent said fulcrum pivot and said lever member having an elongated bearing surface extending adjacent said fulcrum pivot in position to engage said bearing member, said bearing member being adapted, during a power stroke of said lever, to bear upon said surface to turn said lever member on said lever pivot and to ride said surface in a direction outwardly of said lever pivot for power multiplying purposes whereby to raise said rack bar in said frame, a holding pawl pivoted on the frame in position to engage said rack bar and prevent retrogressive movement of the same, spring means normally urging said pawls into operative engagement with said rack bar, and selectively positionable pawl guiding means on said frame for guiding said pawls in a jack lowering operation.

16. A device of the character described comprising a frame, a rack bar forming a lifting jack movably mounted on the frame, a lever member connected for relative turning movement about a lever pivot on said frame, a driving pawl operatively associated with said rack bar and drivingly connected with said lever member, a power lever having an end connected for relative turning movement about a fulcrum pivot on said frame and spaced from said lever pivot, said power lever having a bearing member thereon adjacent said fulcrum pivot and said lever member having an elongated bearing surface extending adjacent said fulcrum pivot in position to engage said bearing member, said bearing member being adapted, during a power stroke of said lever, to bear upon said surface to turn said lever member on said lever pivot and to ride said surface in a direction outwardly of said lever pivot for power multiplying purposes whereby to raise said rack bar in said frame, and a holding pawl pivoted on the frame in position to engage said rack bar and prevent retrogressive movement of the same, said holding pawl having an operative rack engaging head adapted to straddle the driving pawl and engage the rack on opposite sides of the driving pawl.

17. A device of the character described com-

prising a frame, a rack bar forming a lifting jack movably mounted on the frame, a lever member connected for relative turning movement about a lever pivot on said frame, a driving pawl operatively associated with said rack bar and drivingly connected with said lever member, a power lever having an end connected for relative turning movement about a fulcrum pivot on said frame and spaced from said lever pivot, said power lever having a bearing member thereon adjacent said fulcrum pivot and said lever member having an elongated bearing surface extending adjacent said fulcrum pivot in position to engage said bearing member, said bearing member being adapted, during a power stroke of said lever, to bear upon said surface to turn said lever member on said lever pivot and to ride said surface in a direction outwardly of said lever pivot for power multiplying purposes whereby to raise said rack bar in said frame, said lever member carrying said lever pivot extending therefrom on opposite sides thereof and said frame having spaced walls formed with aligned embossments for supporting said lever pivot, said embossments having lateral gates formed therein to allow assembly of the lever pivot radially into the embossments, and bearing members insertable axially in said bosses to journal said lever pivot therein.

18. A device of the character described comprising a frame, a rack bar forming a lifting jack movably mounted on the frame, a lever member connected for relative turning movement about a lever pivot on said frame, a driving pawl operatively associated with said rack bar and drivingly connected with said lever member, a power lever having an end connected for relative turning movement about a fulcrum pivot on said frame and spaced from said lever pivot, said power lever having a bearing member thereon adjacent said fulcrum pivot and said lever member having an elongated bearing surface extending adjacent said fulcrum pivot in position to engage said bearing member, said bearing member being adapted, during a power stroke of said lever, to bear upon said surface to turn said lever member on said lever pivot and to ride said surface in a direction outwardly of said lever pivot for power multiplying purposes whereby to raise said rack bar in said frame, said lever member carrying said lever pivot extending therefrom on opposite sides thereof, said lever pivot comprising a pivot pin, means for supporting said pivot pin in said frame on opposite sides of the lever member, said pawl being mounted on a support pin in said lever member adjacent said pivot pin, one of said pins being relieved on one side to receive the other pin in closely juxtaposed and interfitting relationship to thereby reduce the lever arm between said pins.
